ACCORDION SHIFT MECHANISM

Albert J. Walt, De Kalb, Ill., assignor to The
Rudolph Wurlitzer Company, Chicago, Ill., a
corporation

Application February 28, 1946, Serial No. 650,822

7 Claims. (Cl. 84—376)

1

This invention relates to a shift mechanism and the supporting valve plate therefor operable by a conveniently located shift key or bar to shift the slide valves controlling the treble or bass reed blocks respectively.

The invention is particularly directed to the positive and simplified actuating mechanism operable each time the shift key or bar is depressed to effect a shifting of the slide valves through a spring-controlled linkage mounted upon the valve plate, as hereinafter more particularly set forth and described, reference being had to Letters Patent to Lindeberg No. 2,180,684, granted November 21, 1939, and Morrison No. 2,208,334, granted July 16, 1940.

The full nature of the invention will be understood from the accompanying drawings and the following description and claims:

Fig. 1 is a central vertical section through the valve plate of an accordion bass box.

Fig. 2 is a perspective view of the bass box and bass shift mechanism.

Fig. 3 is the same as Fig. 2, showing the valves shifted to the opposite position.

Fig. 4 is a modified form of the shift mechanism shown in Fig. 2.

In the drawings there is shown a section of an accordion bass box 10 which is apertured to receive thereover a valve plate 11. Said valve plate is apertured to register with apertures of the bass box and the reed blocks indicated at 12, and recessed at 13 to slidably support the slide valves 14, 15.

Fulcrumed upon the valve plate 11 at 16 there is a pair of spaced bell crank levers 17. One end of each of said bell crank levers pivotally carries the lugs 18 of a shift bar 19 operating through an elongated opening 20 in the face of the casting 21.

The opposite end of each of said bell crank levers is pivotally connected to an equalizer bar 22, the rear end of said bar having a tongue 23 connected to a pin 24 by a tension spring 25, said pin 24 being mounted upon the bass box 10. The free end of said equalizer bar 22 terminates short of an oscillator 26 fulcrumed to the box at 27 and provided with an elongated arm 28. Said oscillator is provided with a pair of upstanding pins 29, 29a. Fulcrumed at 30 upon the adjacent end of the equalizer bar 22 there is a shifter finger 31. To one end of said shifter finger there is secured a flat spring 32 extending over and along the equalizer bar with its remote end slidably embraced by the spaced lugs 33. The opposite end of the shifter finger is flared to provide a

2

shifter head 34 formed with adjacent arcuate camming surfaces 35, 35a arranged in camming relation with the pins 29, 29a, respectively.

The free end of the arm 28 has a pin and slot connection at 36 with a reciprocator 37 fulcrumed to the box at 38. Said reciprocator is provided with a pair of upstanding pins 39, 39a slidably extending through transverse slots provided adjacent the ends of the slides 14, 15, respectively. The pin 39a intermediate the fulcrum 38 and pin and slot connection 36 is connected by a tension spring 40 with a fixed pin 41 on the bass box.

In operation, upon depressing the shift bar 19, the equalizer bar 22 will be moved longitudinally toward the oscillator against tension of the spring 25. Cam face 35 of the shifter finger 31 being in engagement with the pin 29 of the oscillator, will swing the oscillator about its fulcrum to thereby cause its arm 28 to correspondingly swing the reciprocator 37 about its fulcrum. This action will throw the spring 40 over center and reverse the position of the valves, all to the position shown in Fig. 3.

In this position, as in Fig. 3, the same action 25 of depressing the shift bar will cause the cam face 35a of the shifter finger engaging the pin 27a to swing the oscillator back to the position shown in Fig. 2, such as to again shift the valves. In each shifting operation, the flat spring 32 30 permits the shifter finger 31 to swivel about its fulcrum 30 in its pushing action upon one or the other pins 29, 29a. But as soon as the shifting pressure is released, said spring acts to return the shifter finger to its neutral position ready 35 for the next shifting action.

Whereas the shift mechanism has herein been shown and described as applied to the slide valves on the bass box, it is similar and in precisely the same manner applicable to the shifting of the 40 valves on the treble box. However, the shift mechanism when applied to the treble box, is operated in the usual manner by a shift key connected with the bell crank lever 17 in place of the elongated shift bar herein shown.

In the modified form shown in Fig. 4, the valves 14, 15 are shifted by a fulcrumed lever 137 in the form of a T-crank. Said lever is biased in over-center position by the spring 140, having one end connected to the fixed pin 141 and the other end 45 connected to the pin 139a which with the pin 139 comprises the pin and slot actuating engagement between the lever and the shift valves. The elongated arm 129 of the oscillator 126 is connected to the arm of the fulcrumed lever 137 by the link 50 55 136. The shift finger 131, operating in the man-

ner above described in respect to the shift finger 31, is retained in its normal position by the coil spring 132 instead of the flat spring 32, as above described. Thus, the shift finger 131 is pivoted at 130 to the equalizing bar 122. The equalizing bar is biased in normal position and actuated by the bar 19 in the manner set forth with respect to the structure of Figs. 2 and 3.

The invention claimed is:

1. In an accordion having a pair of slide valves, a shift mechanism therefor comprising a lever fulcrumed intermediate its ends adjacent the ends of said valves, a pin and slot connection between said lever and valves, an oscillator pivoted to said accordion having an elongated arm, a pin and slot connection between said arm and lever whereby upon oscillation of said oscillator said lever will be swung from one position to another for the shifting of said valves, a depressible actuating member, and means operatively connecting said actuating member with said oscillator for swinging it from one position to the other upon each depressing movement of said member.

2. In an accordion having a pair of slide valves, a shift mechanism therefor comprising a lever fulcrumed intermediate its ends upon said accordion adjacent the ends of said valves, means for operatively connecting the ends of said valves to said lever on each side of said fulcrumed lever respectively, an oscillator pivotally mounted upon said accordion having an elongated arm operatively connected with one end of said lever for swinging said lever and valves from one position to another, over-center biasing means for said lever for yieldingly retaining it in one or the other of its positions, and a depressible member manually operable to swing said oscillator from one position to another upon each depressing movement thereof.

3. In an accordion having a pair of slide valves, a shift mechanism therefor comprising a lever fulcrumed intermediate its ends upon said accordion adjacent the ends of said valves, means for operatively connecting the ends of said valves to said lever on each side of said fulcrumed lever respectively, an oscillator pivotally mounted upon said accordion having an elongated arm operatively connected with one end of said lever for swinging said lever and valves from one position to another, over-center biasing means for said lever for yieldingly retaining it in one or the other of its positions, a shifter bar, a shifter finger pivotally mounted on said bar, spaced projections on said oscillator alternately engageable by said finger to swing said oscillator from one position to another when moved in one direction, and a depressible member manually operable to move said shifter bar and finger in a direction to swing said oscillator to its opposite position on each depressed movement thereof.

4. In an accordion having a pair of slide valves, a shift mechanism therefor comprising a lever fulcrumed intermediate its ends adjacent the ends of said valves, an operative connection between said valves, a lever arranged on each side of said fulcrum point respectively, an oscillator pivoted to said accordion having an elongated arm, a connection between said arm and lever for swinging said lever about its fulcrum point upon the oscillatory movement of said oscillator, a pair of spaced pins on said oscillator, a longitudinal shiftable bar biased in retractable position, a depressible actuating member operatively connected with said bar for moving it from retracted position,

5 and a shift finger pivoted to said bar for alternate actuating engagement with said pins respectively, whereby upon each depression of said member said oscillator will be swung from one position to the other.

5. In an accordion having a pair of slide valves, a shift mechanism therefor comprising a lever fulcrumed intermediate its ends adjacent the ends of said valves, an operative connection between said valves and lever arranged on each side of said fulcrum point respectively, an oscillator pivoted to said accordion having an elongated arm, a connection between said arm and lever for swinging said lever about its fulcrum point upon the oscillatory movement of said oscillator, a pair of spaced pins on said oscillator, a longitudinally shiftable bar biased in retracted position, a depressible actuating member operatively connected with said bar for moving it from retracted position, a shift finger pivoted to said bar for alternate actuating engagement with said pins respectively, and a spring interconnecting said shift bar with said shift finger for biasing said finger in alignment therewith while permitting it to swing against spring tension upon actuation of said oscillator, whereby upon each depression of said member said oscillator will be swung from one position to the other.

6. In an accordion having a pair of slide valves, a shift mechanism therefor comprising a lever fulcrumed intermediate its ends adjacent the ends of said valves, an operative connection between said valves and lever arranged on each side of said fulcrum point respectively, an oscillator pivoted to said accordion having an elongated arm, a connection between said arm and lever for swinging said lever about its fulcrum point upon the oscillatory movement of said oscillator, a pair of spaced pins on said oscillator, a longitudinally shiftable bar biased in retracted position, a depressible actuating member operatively connected with said bar for moving it from retracted position, a shift finger pivoted to said bar for alternate actuating engagement with said pins respectively, and a flat tension spring having its opposite ends connected to said shift finger and bar respectively for biasing them in alignment while permitting said finger to yieldingly follow the movement of the oscillator upon being actuated thereby, whereby upon each depression of said member said oscillator will be swung from one position to the other.

7. In an accordion having a pair of slide valves, a shift mechanism therefor comprising a lever fulcrumed intermediate its ends adjacent the ends of said valves, an operative connection between said valves and lever arranged on each side of said fulcrum point respectively, an oscillator pivoted to said accordion having an elongated arm, a connection between said arm and lever for swinging said lever about its fulcrum point upon the oscillatory movement of said oscillator, a pair of spaced pins on said oscillator, a longitudinally shiftable bar biased in retracted position, a depressible actuating member operatively connected with said bar for moving it from retracted position, a shift finger pivoted to said bar for alternate actuating engagement with said pins respectively, a pair of camming surfaces formed on the end of said shift finger for slidable engagement with said pins respectively, and a spring for biasing said shift finger and bar in alignment while permitting said finger to swing with the corresponding movement of the oscillator and shift to

engagement with the other of said oscillatory pins, whereby upon each depression of said member said oscillator will be swung from one position to the other.
